J. E. CAPS

WATER SOFTENING APPARATUS

Filed Oct. 28, 1918

UNITED STATES PATENT OFFICE.

JOHN E. CAPS, OF WILMETTE, ILLINOIS.

WATER-SOFTENING APPARATUS.

Application filed October 28, 1918. Serial No. 259,901.

To all whom it may concern:

Be it known that I, JOHN E. CAPS, citizen of the United States, residing at Wilmette, in the county of Cook and State of Illinois, have invented certain new and useful Improvements in Water-Softening Apparatus; and I do hereby declare the following to be a full, clear, and exact description of the invention, such as will enable others skilled in the art to which it appertains to make and use the same.

This invention has for its object to provide a novel water softening apparatus of the type adapted to contain a water softening zeolite, such for example as glauconite treated in accordance with the disclosures of the applications of G. L. Borrowman, Patent No. 1,348,977, issued Aug. 10, 1920; and of my co-pending application, Patent No. 1,356,756, issued Oct. 26, 1920.

The invention has for its particular object, to provide a simple semi-automatic water softening apparatus of the aforesaid type in which regeneration is effected partially by a manual operation, followed by an automatic operation as hereinafter more fully described, whereby the apparatus is automatically restored to service after each regeneration.

The invention consists in the features of construction and combinations of parts hereinafter fully described, and particularly claimed.

The accompanying drawing illustrating the preferred embodiment of the invention, shows apparatus constructed in accordance with my invention, partly in section and partly in elevation.

My said apparatus comprises a filter consisting of a cylindrical drum 1 provided with a centrally located opening 2 in its bottom, adapted to be closed by means of an ordinary man-hole cover 3 of the type used in boiler construction. Said drum is further provided at its upper end with a suitable grate 4 or similar foraminous element which constitutes the bottom of a hollow cover 5 adapted to contain salt. Said cover is provided with a central opening 6 in its top wall which is closed by means of a cap 7 pivotally mounted on a lever 8 having a bifurcated end 9 opposite its pivot 10 in which the shank of a pivoted and threaded rod 11 engages, the latter being equipped

with a hand-wheel 12 for forcing the plate 7 down upon the annular flange bordering the opening 6 in a well known manner.

Contiguous to the top of the drum 1 and below the cover 5, which is removably mounted thereon, is a boss 13 in which one end of a horizontal pipe 14 is fitted. The latter connects with the pipe 15 extending centrally vertically through the drum and which, at its lower end, is coupled with horizontal branches 16 each of which is provided with a plurality of elbows 17 having downwardly extending free end portions in the mouths of which strainers may be fitted. The said pipe 14 connects with a pipe 18 equipped with a three-way valve 19 by means of which said pipes 14 and 18 connect with a service pipe 20 and a drainpipe 21. The handle 22 of the valve 19 is pivotally engaged between its ends with a plunger or piston rod 23 connected with the piston 24 reciprocable in a cylinder 25. The said cylinder is connected at respectively opposite ends with pipes 26 and 27 separated from each other and both connected with a pipe 28 by means of a four-way valve 29 controlled by a hand lever or stem 30. The pipe 28 connects with the water supply and is adapted to deliver water under pressure alternately to opposite ends of the cylinder 25 to effect reciprocation of the piston 24 as and for the purposes hereinafter fully described.

The pipe 28 is connected by means of a T-coupling 31 with a supply pipe 32 leading into the cover 5 above the grate 4. The pipe 32 connects with the branch-pipe 33 through the three-way valve-housing 34 controlled by the three-way valve operable by means of a lever 35. The latter is coupled with the lever or handle 30 by means of the connecting rod 36. The pipe 33 connects with the drainpipe 21 and also by means of a T-coupling 37 with a relief pipe 38 which connects with the pipe 27 contiguous to the connection of the latter with the lower end of the cylinder 25. A check valve 39 is disposed in pipe 27 between valve 29 and the connection of the pipe 38 therewith. In said pipe 38 a cock 40 is interposed by means of which the flow of water under pressure through said pipe 38 from the cylinder 25 may be regulated and controlled as desired for the purpose of determining the time required to

cause the piston 24 to complete its upward stroke after it has been lowered, as herein-after described. The water passing upwardly through the pipe 38 passes from the 5 T-coupling 37 into the drain pipe 21. The pipe 28 is further connected by means of a T-coupling with a small supply pipe 41 which connects with the pipe 18 between the valve 19 and the boss 13 there being a 10 valve 42 interposed between the ends of said pipe 41. The cylinder or drum 1 is partially filled with a layer of rather finely crushed rock upon which a layer of fine gravel is disposed. Above the layer of gravel and substantially to the level of the grate 4 the drum or cylinder 1 is filled with the zeolite water softening substance. 15 The operation of my device is as follows: 20 Normally, the housing 1 is connected with the water supply pipe 28 from which water flows through pipe 32 into the cap or cover 5 thence through the filter bed of zeolite, gravel and crushed rock, upwardly through 25 the elbows 17 and pipes 16, 15, 14 and 18 and valve housing 19 to the service pipe 20 for consumption wherever desired. The water is softened during the period of its flow through the zeolite which becomes exhausted 30 after a given amount of water has passed therethrough and has reacted thereon to become softened in the usual and well-known manner. When said zeolite is so exhausted it must be regenerated by passing brine therethrough. 35 To this end the valve stem 35 is raised by turning the same through an arc of about ninety degrees thereby shutting off the flow of water into the cap or cover 5 and through the drum 1. The valve 29 is 40 turned simultaneously with the valve 34 and causes water to flow from pipe 28 into pipe 27 and thence into the lower end of the cylinder 25, thus causing the piston 24 to rise and automatically turn the valve 19 so as to 45 connect the pipes 18, 14, etc., with the drainpipe 21. During upward movement of the piston 24, the water in the upper end of cylinder 25 will be forced into the drainpipe 21. The cap 7 is now removed from the 50 cover 5 and the requisite quantity of common salt is then introduced into said cover 5 and the cap 7 thereupon replaced. Then the valve stem 35 is returned to its normal position, thus re-establishing connection between the cover 5 and the water supply pipe 28. This will cause water to flow through the cap 5 and the salt therein contained, thus 55 dissolving the latter and causing the brine thus formed to flow through the filter bed and then up through pipes 16, 15, etc. to drainpipe 21. As soon as the valve 29 is returned to its normal position, as shown, the pipe 28 is connected with the pipe 26 and thus with the upper end of the cylinder 25. 60 65 This causes the piston 24 to be returned to

its normal position, but in order to accomplish this, it is obviously necessary that the water in the lower end of the cylinder must be exhausted. This is resisted by cock 40 which, if closed, would obviously prevent 70 downward movement of the piston. By very slightly opening the same the flow from the lower end of the cylinder into the drainpipe 21 will obviously be very slow and gradual, 75 so that it will take a considerable space of time for valve 19 to be returned to its normal position to interrupt communication of the pipe 18 with the drainpipe 21 and establish connection between the same and the service pipe 20. The cock 40 is normally positioned 80 so as to maintain the valve 19 open for a length of time sufficient to cause all of the salt contained in cap 5 to be dissolved, and to flow through the filter bed and also to 85 permit a flow of fresh water through the filter bed following the flow of brine to flush said bed and entirely cleanse the same of any traces of the brine. The valve 42 is normally closed but at intervals, when desired, it may be opened during periods when the lever 35 and accordingly the handle 22 are both 90 raised, thereby causing a flow of water in the opposite direction from normal through the pipes 18, 14, etc., and from the bottom to the top of the filter bed for the purpose of 95 loosening up the material composing the same which is apt to become very tightly packed after a continuous flow of water in one direction therethrough for a long period of time and which, therefore, is apt to resist the relatively free flow ordinarily desired, thereby placing the filter bed in condition for most economic operation. 100

This upward flow through the filter bed also serves, as is well known, to carry off foreign matter from the upper portions of the filter bed. The water carrying this foreign matter will be drained off through the pipe 32 which connects with the drain 21 through pipe 33 when the lever 35 is disposed in the position shown in dotted lines. 105

While I have illustrated the preferred embodiment of the invention in the accompanying drawings it will be obvious, of course, that the same may be changed and varied in 115 the details without departing from the invention as defined in the appended claims.

I claim as my invention:

1. Water softening apparatus comprising a housing for a bed of zeolite, a salt chamber connected therewith, means for introducing salt into said chamber at intervals, a water supply pipe connected with the chamber, and a service pipe connected with the housing relatively arranged to cause water 120 to flow through the bed of zeolite from the chamber to the service pipe, a drain pipe connected with the service pipe, a three-way valve normally maintaining the housing connected with the service pipe and adapted 125 130

- to be positioned to connect the same with the drain pipe, fluid pressure actuated means for actuating said valve, connection between the fluid pressure actuated means and water supply pipe, a valve controlling the same for causing said three-way valve to be turned to either of its two positions, means for controlling the speed of movement of said three-way valve in one direction, a valve controlling the water supply to said chamber, and connection between said water-controlling valve and the valve controlling the pressure actuated means for causing the same to open and close in unison.
- 15 2. Water softening apparatus including a container for zeolite, a salt chamber connected therewith, means for introducing salt into the latter at intervals, a water supply pipe and a service pipe connected with said salt chamber and said container respectively for causing water to normally pass through the zeolite from the first-named to the last-named pipe, manually operable means for interrupting the connection between the water supply pipe and said chamber during intervals of introducing salt into the chamber, a pipe drain for said container, and a fluid pressure actuated valve controlled by said manually operable means for automatically connecting said container with said drain and disconnecting the container from said service pipe as the supply of water from the supply pipe is shut off and to maintain said connection with said drain and disconnection from said service pipe for a predetermined interval of regeneration and flushing of said container, and thereafter upon returning said manually operated means to normal position automatically disconnecting
- said container from said drain and connecting it with the service pipe.
3. Zeolitic water softening apparatus including a zeolite filter bed, means for passing water to be softened thru the same including a service pipe, manually operable means for passing a regenerating solution through the bed at intervals, fluid pressure actuated means associated with and controlled by said manually operable means for automatically effecting by-pass of the regenerating solution from the service pipe and thereafter upon manual restoration of said manually operable means to normal position automatically restoring flow of soft water thru said service pipe.
4. Water softening apparatus including a zeolite filter bed, a water supply pipe and service pipe arranged to cause water to flow from the former to the latter through said bed, a salt chamber disposed between the filter bed and supply pipe, and adapted to be manually charged with salt at intervals, a drain for the filter bed for drawing off brine, manually operable means for shutting off flow of water during intervals of charging of said salt chamber, and fluid pressure actuated means associated with said manually operable means and said supply pipe and controlled by the former for automatically connecting said filter bed with said drain and disconnecting it from the service pipe during a period beginning with the shutting off of flow from the supply pipe and terminating after the lapse of a predetermined time interval after said flow from the supply pipe has been restored.

JOHN E. CAPS.
